UNITED STATES PATENT OFFICE

2,550,754

HEATING APPARATUS

Augustus L. Baker, Wrentham, Mass.

Application May 14, 1946, Serial No. 669,604

3 Claims. (Cl. 257—137)

1

This invention relates to heating apparatus intended primarily for domestic purposes, although useful, also, in other situations.

It aims to devise an apparatus of this character which will be highly efficient; may be assembled and installed as a unit; will occupy little space; and which will distribute heat with a high degree of uniformity. It is also an object of the invention to devise such a construction so organized that it can be used for cooling in summer, as well as for heating in winter; and one which can be easily modified to accommodate the requirements of a wide variety of home arrangements and conditions peculiar to individual installations.

The nature of the invention will be readily understood from the following description when read in connection with the accompanying drawings, and the novel features will be particularly pointed out in the appended claims.

In the drawings,

Fig. 1 is a perspective view of a heating unit embodying the present invention;

Fig. 2 is a similar view of the fan section of the unit shown in Fig. 1;

Fig. 3 is a similar view of the filter section;

Fig. 4 is a front elevation with parts of the cabinet broken away;

Figs. 5 and 6 are sectional views taken approximately on the lines 5—5 and 6—6, respectively, of Fig. 4;

Fig. 7 is a front elevation showing a modified air circulating arrangement which may be used with the unit shown in Fig. 1; and

Fig. 8 is a side elevation, partly in section, of the arrangement illustrated in Fig. 7.

Referring first to Figs. 1 to 6, inclusive, the organization there shown comprises a casing or cabinet 2 which preferably extends from the floor to the ceiling and may be made of any suitable material, such as wood, metal, or combinations of the same. It is provided at its lower end with an air inlet 3, and at its upper end with an air outlet 4. Between these openings is a heating unit 5 which, in the particular form shown, is designed for the circulation therethrough of steam, vapor, or hot water. It is mounted in a fixed position on angle irons 1—7 supported in the walls of the casing, and for convenience of installation the supply and return pipes 8 and 9, respectively, are arranged in sections secured together releasably by couplings 10 located in the lower chamber or compartment of the casing where they will transmit heat to the air flowing inwardly from the opening 3 and upwardly in the

2

casing around the heating unit 5 and later discharged through the outlet 4.

While such circulation of air would be created thermally, it would be relatively slow, and a fan 12 consequently is positioned in the top of the casing where it is driven by an electric motor 13. It speeds up the circulation of air through the casing very substantially and therefore contributes materially to the efficiency of the apparatus.

Immediately below the heating unit 5 is a filter 14 extending across the air space in the cabinet so that the entire flow must pass through the filter. It may be made, in general, of such constructions as those used in heating and air conditioning equipment, but should offer as little resistance to the flow of air as is consistent with effective filtering. Preferably it is made in the form of a drawer including a front plate or panel 15 which forms, when the drawer is closed, part of the front wall of the cabinet or casing, and rails 16—16, Fig. 3, rigid with said panel, extending rearwardly therefrom, and slidable on bars 17—17, Fig. 4, mounted in the opposite lateral walls of the cabinet. When in its normal position the panel 15 tightly closes the opening provided to receive it in the front face of the casing. By positioning the pipes 8 and 9 closer to the rear wall of the lower chamber the length of the slots 15 provided in the filter to receive them may be reduced to negligible proportions. Or these spaces may be closed in other ways.

Preferably the entire inner wall surface of the cabinet is covered with heat insulating material 19 and the inner surface of this material, in turn, is lined with metal foil, or some equivalent heat reflecting medium. This is decidedly preferable in the upper chamber in which the heating unit 5 is located, but is not so essential, although it is also preferable, in the lower chamber. If this inner surface also is corrugated, as shown in Figs. 4 and 6, the efficiency is somewhat improved, particularly in the upper chamber.

While this invention may be embodied in forms varying substantially in size, some being intended to heat only a single room, it is contemplated that the maximum advantage of the invention will be realized when it is embodied in larger units, each designed to take the place of a considerable number of the conventional radiators. I have found, by experience, that a single unit will heat several rooms, if they are compactly located. Consequently, a single cabinet equipped, as above described, can be used to heat all the rooms on the lower floor of a small house, and

another can be used to heat the rooms in the second story.

The action which occurs when the apparatus is so used seems to be that the air is heated rapidly as it flows upwardly through the cabinet and it is discharged just below, and closely adjacent to, the ceiling level. It spreads out across the ceiling and, as the further discharge of heated air occurs, and the coolest air is drawn from the room in which the cabinet is installed and from the adjoining rooms connected with it by the usual door-ways, the entire body of warmer air in each room settles. The heated air flows from the room in which the cabinet is located through the doorways into the adjoining rooms, where it rises to the ceiling and takes the place of the coolest air withdrawn along the floor level by the suction created at the intake opening 3 in the cabinet. In this way several rooms are kept warm with a single heating unit, such as that shown in Fig. 1.

If desired, fresh air may be led in from out of doors through the duct or conduit 18, Figs. 1, 4 and 6, which opens into the lower chamber in the cabinet and this supply of air can be controlled by a damper or shutter 20 operated by the knob 21. In very cold weather such inflow of air ordinarily will not be used.

This outside supply of air, however, is useful in summer when air may be taken from the cool side of the house, or from an enclosure built especially for the purpose and can be drawn in and circulated by means of the fan 12, the heating unit 5 at this time being cold or unwarmed. And this cooling effect can be materially improved by circulating a cool brine or other heat absorbing medium through the unit 5, thus serving to modify very substantially the indoor temperature.

In the latter event, it will be preferable to draw air from the upper part of the room through the opening 4 and to discharge it through the lower opening 3 which normally serves as an air intake. Partly for this purpose, and also to facilitate inspection and repairs, the fan is so supported as to be easily withdrawn from the cabinet. As best shown in Figs. 2, and 4 to 6, a drawer-like construction is provided for this purpose. That is, the fan is mounted on a transverse beam 22 of channel section, the ends of which are welded to channel-shaped slides 23-23 running on stationary bars 24-24 in essentially the same manner that the filter 14 is supported. These channels 23 also are welded to the front face plate section 25 which extends entirely around the opening 4. Consequently, this whole fan unit, or assembly, including its support and its motor, can be withdrawn from the cabinet, whenever desired, as for inspection or repairs.

In order to permit this unit to be placed in the bottom of the cabinet, as above indicated, another slide containing the inlet opening 3 and including the same kind of a frame structure used in the fan slide, is provided at the bottom of the cabinet and is shown at 26. It includes channel bars 23', Fig. 4, running on stationary bars 24', and this lower drawer or slide is made of the same dimensions as the corresponding parts of the fan slide, so that when the latter is removed it can be substituted for the lower slide 26, and the latter can be installed at the top of the cabinet. In other words, the two are interchangeable. This is very desirable when a cooling medium of any kind is circulated through the unit 5.

When it is desired to use a heating unit of this

character, not only to heat the rooms on the lower floor, but also one or two in a floor above it, such an arrangement as that shown in Figs. 7 and 8 may be employed. Here a duct or conduit 5 27 is connected at its lower end with the port or outlet 28, Fig. 6, of the cabinet 2 and is led upwardly through the ceiling of the room below to a point close to the ceiling in the room above. At the upper end of this conduit a casing is 10 formed to take a fan unit like that shown in Fig. 2. In Fig. 8 this fan is shown at 30. Normally any flow of air through the port 28, Fig. 6, is prevented by a hinged plate or damper 31, but when the upstairs connection 27 is used, this 15 damper is turned into its open position, as shown in Fig. 8, where it is held by a latch 32, so that under these conditions the air heated in the cabinet 2 is divided, part of its being discharged into the room in which the cabinet is located and the remainder flowing upwardly through the duct 27 and being delivered by the fan 30 just below the ceiling level in the upper room.

The cool air in the latter room flows down through a register 33, Fig. 7, in the floor of said 25 room and through a duct 34 which delivers it into the lower chamber of the casing or cabinet 2 at the side opposite the fresh air duct 18. This down flow of air may be controlled by a damper or shutter like that shown at 20, and operated by a knob or handle. Further control of the distribution of air between the upstairs and downstairs rooms may be afforded by pivotally mounting the shutters on the fan unit and connecting them together, as by a rod 36, Fig. 2, so that by 30 turning one, all of them will be adjusted to shut off more or less of the air discharged by the fan 12. The same construction will be provided to 35 cooperate with the fan 30, and shutters so arranged may be used at the intake opening 3.

40 As shown in Figs. 5 and 6, the casing includes partition plates 38 and 40 which cooperate to form a chamber in which the motor 13 is housed; but the partition 38 is provided with an aperture through which the motor may be withdrawn. 45 Normally this aperture is closed by a plate 41, Fig. 3, rigid with the motor and its mounting.

The invention thus provides a heating unit which eliminates the necessity for the conventional radiators; simplifies the heating system; 50 improves the efficiency of that system; and distributes the heat to the areas at which it is needed with a high degree of uniformity. It can be used to modify the room temperatures not only by heating them, but also by cooling them, and 55 with the aid of such supplemental ducts as those above described, the installation can be modified to accommodate the great variety of conditions found in different homes. Moreover, with the form of the invention shown in Figs. 7 and 8, either the group of rooms downstairs or those on the second floor can be heated to the exclusion of the other, or both groups may be heated, as desired.

Having thus described my invention, what I 60 desire to claim as new is:

1. An apparatus of the character described, comprising a casing constructed to extend substantially from the floor to the ceiling of a room and provided with lateral air openings in its upper and lower end portions, a heating unit in said casing between said openings, said unit exposing a large area to contact with the air flowing from one of said openings to the other, an air circulating assembly comprising a fan, a motor driving it, and a drawer-like structure on which said fan

and motor are supported, said casing being provided with recesses near its top and bottom, in either of which said assembly may be mounted selectively to force air through said casing either up or down, as desired.

2. An apparatus of the character described, comprising a casing constructed to extend substantially from the floor to the ceiling of a room and provided with lateral air openings in its upper and lower end portions, a heating unit in said casing between said openings, said unit exposing a large area to contact with the air flowing from one of said openings to the other, an air circulating assembly comprising a fan, a motor for driving said fan, a support on which said fan and motor are mounted, said assembly being positioned in said casing substantially in alignment with one of said lateral openings to force air therethrough, and said casing having guides on which said support is mounted for the sliding movement of said assembly into and out of said casing.

3. An apparatus according to preceding claim 2, in which said air circulating assembly also includes a grill mounted on the support for said fan and motor and adapted to fit snugly into the

opening in said casing with which said assembly is positioned to cooperate.
